WALL MOUNTED LIGHTING FIXTURE

Martin L. Lasker, North Valley Stream, N.Y., assignor to McPhilben Manufacturing Co., Inc., Brooklyn, N.Y., a corporation of New York

Filed Mar. 5, 1962, Ser. No. 69,090

Term of patent 14 years

(Cl. D48—4)

FIG. 1

FIG. 1 is a front elevation of a wall mounted lighting fixture, showing my design;

FIG. 2 is a side elevation of the same; and
FIG. 3 is a bottom view of the same.

The rear of the fixture is substantially plain.

I claim:

The ornamental design for a wall mounted lighting fixture, substantially as shown and described.
